Horace G. Seitz

UNITED STATES PATENT OFFICE.

JULIUS SCHIRRA, OF PITTSBURGH, PENNSYLVANIA, ASSIGNOR TO PROJECTILE
PROTECTOR COMPANY, OF WILKINSBURG, DELAWARE, A CORPORATION OF
DELAWARE.

THREAD-PROTECTING DEVICE.

1,803,402.

Specification of Letters Patent. Patented May 13, 1919.

Application filed May 11, 1917. Serial No. 167,870.

To all whom it may concern:

Be it known that I, JULIUS SCHIRRA, a citizen of the United States, residing at Pittsburgh, in the county of Allegheny and State of Pennsylvania, have invented a new and useful Improvement in Thread-Protecting Devices, of which the following is a specification.

The present invention relates to improvements in thread protecting devices, pertaining more particularly to devices adapted to protect the threaded ends of pipes, bars, etc.

The threaded ends of pipes, bars, etc., are subject to damage to the threads unless the latter be protected, either by the use of a member threaded thereto or the use of a protecting device which overlies the threads and thus protects them from damage.

Devices for this purpose have heretofore been provided, but they are more or less expensive, if of any material value for protecting purposes. The present invention is designed to produce devices for this purpose at comparatively low cost, capable of ready application, and provide for efficient protection.

To these and other ends, the nature of which will be readily understood as the invention is hereinafter disclosed, the invention consists in the improved construction and combination of parts, hereinafter fully described, illustrated in the accompanying drawings, and more particularly pointed out in the appended claims.

In the accompanying drawings, in which similar reference characters indicate similar parts in each of the views,—

Figure 1 is a view in elevation showing a device of the present invention in position on the threaded end of a pipe.

Fig. 2 is a sectional view taken diametrically through the pipe and device.

Fig. 3 is a detail sectional view taken on line 3—3 of Fig. 2.

Pipe threads, especially when external, are easily damaged, owing to the particular thread configuration, together with the fact that slight mutilation may affect the ability to thread the complementary member thereon.

This can be avoided to a more or less extent by protecting the threads with a member threaded temporarily thereon, but this requires the use of a member having threads

complementary to the pipe threads, and where the pipe is subject to exposure, may produce a rusted condition which becomes troublesome. To meet this condition and at the same time provide for threads of different pitch, it is preferable to employ a protector which does not thread on to the pipe threads, but overlies such threads in such manner as to protect them.

The present invention meets this condition by the use of a one-piece member in strip-form and having its opposite ends connected together to produce a device somewhat similar to an open-ended cap. This cap is preferably formed of a tough, more or less fibrous material which, when shaped, is strong and durable. A preferred material is that known as "commercial fiber," a product produced in sheet form having a ply of considerable thickness. This material, while more or less rigid, can be rolled and shaped without materially affecting its texture.

In producing the device, a blank is formed from the flat sheet of material, the blank having a length sufficient to provide an overlap of ends when the strip is in ring form, the blank having a width sufficient to provide the skirt and the return portion which overlies the skirt, as indicated in Fig. 2, the blank preferably having a cut-away portion at one corner for a purpose to be described.

The device, indicated at 12, is corrugated along one edge, as at 12^a, this forming the outer portion of the skirt 12^a. The opposite edge of the blank is then bent over on to the skirt, forming a reinforce for the outer portion of the device, and the band then rolled into a somewhat circular form, the rolls having a configuration to produce an annular external bulge 12^b (and the complementary annular internal depression 12^c) adjacent the line of bend, the latter, of less diameter than the skirt, forming a lip 12^d, the inner face of which is adapted to abut against the end of the pipe 10 and limit the inward movement of the device over the threads 10^a.

As shown in Fig. 1 the blank is cut away a distance substantially equal to the length of the overlapping ends, the arrangement enabling the skirt portion of the cut-away end to be inserted between the skirt and return portion of the opposite end when the two ends are connected together by suitable

means, as for instance a rivet 13, the inserted skirt end being indicated at 12^t and forming the overlying portion of the skirt in Fig. 1.

As will be seen, the diameter of the lip 12^d is less than the diameter of the skirt, while the diameter of the bulge is greater than that of the skirt. The ability to produce these differences in diameter, as well as permit the ring formation, when the particular material indicated is employed, is due to the corrugated formation which permits the material to take its proper shape without affecting the general characteristics of the sheet from which it is formed.

15 The general configuration shown limits the amount of inward movement of the device through contact of the lip with the end of the pipe or bar, while the bulge arrangement presents an outer face adapted to receive the shocks and jars without liability of damaging the threads, the reinforce provided by the double thickness of material so stiffening the structure as to insure its proper efficiency.

20 25 The completed device can be readily positioned and removed, can be produced in standard sizes of pipe at a comparatively low cost, possesses the desired rigidity, is able to sustain the ordinary shocks and jars 30 and is of a material which may be driven on to the threads under excessive pressure without damaging the latter, and which will permit of being thrown away, if desired, without material loss due to the low cost of 35 manufacture.

While I prefer to employ material of the type indicated, the device may be formed from other materials capable of manipulation to produce the structure shown and 40 such other materials are considered as falling within the invention.

While I have shown a preferred arrangement, it is to be understood that changes or modifications therein may be required or desired to meet the various exigencies of use, and I desire to be understood as reserving the right to make any and all such changes or modifications therein as may be found desirable or necessary, in so far as the same 45 50 may fall within the spirit and scope of the invention as expressed in the accompanying claims when broadly construed.

Having thus described my invention, what I claim as new is:

55 1. A thread protecting device comprising a strip of fibrous material of greater length than the circumferential length of the device, said strip being shaped to provide a ring-shaped exterior having different diameters and overlapping ends with the differ-

ence in diameters compensated by corrugations, and means for securing the ends together.

2. A thread protecting device comprising a ring-shaped band formed from sheet fiber, 65 said band having a skirt and also having portions projecting beyond the planes of the inner and outer diameters of the skirt, the differences in diameter being compensated by corrugations, the ends of the band being 70 in overlapping relation and secured together.

3. A thread protecting device comprising a band formed from sheet fibrous material, 75 said band having a skirt, a lip of less diameter than the diameter of the skirt, and an annular bulge of greater diameter than the skirt diameter, said skirt carrying means to compensate for the differences in diameters.

4. A thread protecting device comprising a band formed from a strip of sheet fibrous material, said strip being folded upon itself to form a skirt and a portion overlying the skirt, said line of fold being formed to produce a lip having an internal diameter less than the diameter of the skirt, said skirt carrying means to compensate for the differences in diameters.

5. A thread protecting device comprising a strip of sheet fibrous material folded upon itself to produce a skirt and a portion overlying the skirt to produce a two-ply structure adjacent the line of fold, said double-ply structure having an annular external bulge, said skirt carrying means to compensate for the differences in diameters.

6. A thread protecting device comprising a band formed from a strip of sheet fibrous material folded upon itself to produce a two-ply structure, one of the plies forming a skirt, said two-ply structure having an annular external bulge and an annular internal depression, said skirt carrying means to compensate for the differences in diameters.

7. A thread protecting device comprising a strip of sheet fibrous material adapted to produce a band formation with overlapping strip ends, said strip being folded upon itself to produce a skirt and an overlying portion of less width than the skirt and forming a two-ply structure adjacent the line of fold, said two-ply structure having an external annular bulge and an annular lip, 110 said lip having a diameter less than the diameter of the skirt, said skirt carrying means to compensate for the differences in diameters.

JULIUS SCHIRRA.
